FALLING FILM EVAPORATOR

Joseph A. Cross, Westerville, Ohio, assignor to
 Mojonier Bros. Co., Inc., Chicago, Ill., a corporation of Illinois

Application September 9, 1946, Serial No. 695,641

4 Claims. (Cl. 159—13)

1

This invention relates to evaporators and particularly to those designed for continuous rather than batch operations.

A feature of the invention resides in the provision of multi-stage evaporation, not according to the usual multiple effect wherein the hot vapors of one stage heat the liquor in the next, but rather by maintaining segregated bodies of liquor of different densities heated from a common heat supply source and connected to a common vapor exhaust.

While the apparatus is suitable for evaporation at various pressures and temperature levels, it offers especial advantages at the low temperatures obtainable under vacuum.

One of the objects of the invention is to provide evaporation apparatus suitable for continuous operation and using tubular evaporators of the falling film type.

Another object of the invention is to provide a multi-stage evaporator system in which the liquor progresses through connected bodies of the liquor maintained at different densities and subjected to evaporation by heat supplied from a common source of condensable vapor.

Other objects and advantages of the invention will be apparent from a perusal of the following specification wherein a preferred and a modified embodiment of the invention are described.

On the drawings:

Figure 1 is a side elevation of an evaporator made in accordance with this invention;

Figure 2 is a top plan view of the same evaporator;

Figure 3 is a sectional view on the line III—III of Figure 1;

Figure 4 is an end view of the evaporator;

Figure 5 is a partial sectional view of one of the elements of the evaporator taken on the plane of line V—V of Figure 1;

Figure 6 is a partial sectional view taken on the plane of line VI—VI of Figure 4;

Figure 7 is a side elevation of a modified form of the evaporator units; and

Figure 8 is a sectional view on line VIII—VIII, of Fig. 7 with the lower portion of one evaporator also in section.

Figure 9 is a horizontal sectional view on the line IX—IX of Fig. 7.

Referring first to Figs. 1 to 6 of the drawings, the evaporator is comprised of an assembly of substantially identical units interconnected in order to afford a system of multi-stage evaporation. Each unit includes a vertical tube chest

2

such as the chest 1. Each tube chest contains a plurality of tubes such as 2 held in the upper and lower tube sheets indicated as 3 and 4, in Figures 5 and 3, respectively. The upper ends of the tubes open into a chamber 5 at the top of each tube chest, into which the liquor to be evaporated is introduced by means of a pipe 6.

As stated before, the evaporator units are of the falling film type. Accordingly, in order to feed the liquor into the evaporator tubes in the form of films I provide a removable tube 7 inserted into the top end of each evaporator tube 2, and supported by spiders 8 which may be welded or otherwise secured to their outer surfaces, the three or more legs of the spiders resting upon the upper tube sheet 3. The lower end of each tube 7 is flared out at 9 to restrict and deflect the downwardly flowing liquor against the tube walls. The rate of flow of liquor into the tubes 2 of each evaporator may be varied by increasing the depth of the body of liquor maintained above the upper tube sheet 3, by regulating the rate of delivery of liquor through the pipes 6 into the chambers 5. The static head 10 thus will determine the rate of flow of the film and may be controlled to assure the maintenance of a film in each tube to its bottom end. Of course, overflowing the top of the tubes 7 is to be avoided. The top of each chamber 5 will be closed by a cap 10.

The heating medium, such as steam, a refrigerant gas, or other condensable vapor is preferably introduced into the upper portion of each tube chest from a common supply pipe 11 connected with an individual supply pipe 12 leading to each tube chest. The condensate which may be drained from the space around the tubes at the bottom of each tube chest may be withdrawn from each tube chest through a pipe 13 into a common pipe 14.

Directing attention now to the construction at the lower end of each tube chest, it will be noted that a generally cylindrical device is associated with each of the tube chests at their lower ends. 45 These devices are a series of drums 15 having abutting inwardly extending flanges 16 which preferably will be welded together. These flanges do not extend across the entire diameter of each drum but instead are apertured at 17 thus 50 providing a common passage through which vapors from the evaporating liquor may be withdrawn rapidly from the respective drums and tube chests to a common duct or pipe 18. At the bottom end of each tube chest is a curved hood 19 which opens into the adjoining drum

15 and also into the associated sump 20, there being one such hood and one such sump for each tube chest.

Each chamber 15 preferably will have an ar-
cuate baffle 15' secured to the margin of opening 17, which will assist in imparting centri-
fugal motion about a horizontal axis to the
vapors and prevent their more direct escape
through the ports 17. Thus, the vapors being
extracted from the falling film of liquor are 10
deflected in a circular path from the lower open
ends of the tubes into the related drums 15,
while any unvaporized liquor is allowed to fall
through the hood 19 into the sump 20.

As indicated, there is connected with the bot-
tom of each sump a pipe 21 leading to a pump
22, each pump being preferably driven by an
electric motor and delivering its output to a riser
pipe 6, which as noted before delivers the liquor
into the chamber 5 at the top of each tube
chest.

The fresh dilute liquor to be evaporated will
be introduced through a pipe 23 into the down-
flow pipe 21 of the first evaporator unit where
it will be drawn through the pump 22 and thence
delivered upwardly through the riser pipe 6 into
the top of the first evaporator chamber 5. It is
contemplated that some of the liquor will re-
circulate through the first evaporator unit many
times as the vapor is being extracted from it
in the falling film tubes.

A draw-off pump 24 connected with the draw-
off pipe 25 maintains a continuous discharge of
concentrated liquor from the last evaporator. 35
Between the first and second units, that is,
connected with their sums, is a pipe 26 and
between the sump of the second unit and the
sump of the third unit is another pipe 27. The
operation of the draw-off pump and the feed of
fresh liquor through the pipe 23 will therefore
induce a continuous flow of liquor from the first
unit to the second and from the second to the
third and from the third to the draw-off pump
or to such other units as may be connected be-
tween that point and the draw-off pump.

While three connected units are shown in the
evaporator herein described, it is contemplated
that as many as are necessary for high output
and efficiency of operation will be employed. In
view of the fact that the units are identical in
construction, the cost of manufacture and as-
sembly is thereby simplified. Also, the use of
identical units simplifies the determination of
ideal operating conditions and facilitates the
determination, by experiment or by calculation,
of the number of units required for the most ef-
ficient operation on any proposed installation.

The operation of the device, briefly, is as fol-
lows:

Fresh liquor is supplied through a pipe 23 to
the down-flow pipe leading to the pump con-
nected with the first unit. This liquor along with
other liquor already in the system is delivered
to the top of the first unit and under the con-
trolling effect of the static head and the tubes
7 will cause a film of the liquor to flow down-
wardly along the entire inside of each of the
tubes in the first unit. While liquor is being re-
circulated through the falling film unit the vapor
released from the films flows from the lower ends
of the tubes into the vapor separation drum.
The circular motion imparted to the vapor will
cause entrained droplets to sweep along the walls 75

of the drum and fall back into the sump of each
drum while the vapor, free from droplets, may be
evacuated through the vapor outlet pipe 18.

The rate of evaporation will be highest in the
first unit and lowest in the last evaporator unit.
As a result the second unit will be operating on
a liquor of considerably higher density than the
fresh liquor introduced into the first unit. The
liquor flowing from the second unit to the third
unit will have an even higher density, and dur-
ing its recirculation and subjection to evapora-
tion in the third unit may be caused to attain
the final desired density. The rate of with-
drawal of liquor through the draw-off pipe 25
will be maintained at such a rate as to make cer-
tain that liquor of the desired density only is
withdrawn.

It is clear that a large number or a small num-
ber of identical units may be connected in series,
20 as described, in order to obtain a desired con-
centration under efficient operating conditions.

As stated hereinbefore, the present invention
is especially suitable for evaporation of liquors
25 at low temperatures such as are made possible
by evaporation under vacuum. In such case,
suitable equipment is connected with the vapor
outlet pipe 18, that is, such as pumps or con-
densers or both, to maintain as high a degree of
vacuum in the vapor space within the drums and
within the tubes as may be desired.

Obviously, the means for evacuating the va-
pors will be suited to whatever vapor pressures,
positive or vacuum, prevail in the system. Vari-
able speed pumps, valves, or other devices may
be employed for maintaining uniform or pro-
viding variable operating conditions.

In Figures 7 and 8 I have shown a modified
40 form of the evaporator units, the modification
consisting in a different vapor separation device
at the bottom of each evaporator unit, to cause
the vapors to rotate about a vertical axis, in-
stead of a horizontal axis as in the units here-
45 tofore described.

In this modification I have shown three ver-
tical tube chests 30, the upper ends of which will
50 be constructed as are the tube chests in Figures
1 and 5, being provided with insertable tubes in
their upper ends for producing a film flow and
assisting in regulating the rate of flow. The
lower ends of the tubes, however, do not open
55 directly into the vapor separator drum or hood
as do the tube chests shown in Figure 3. In-
stead, the vapors and unvaporized liquor emerge
from the lower ends of the vertical tubes, through
lower tube plates 31 and fall into the chambers
60 32 and then flow outwardly through the hori-
zontal ducts 33 and enter tangentially into the
associated vertical separator cylinders 34. The
unvaporized liquid, being thrown centrifugally
against the walls of the cylinders 34 by the force
65 of the rapidly flowing vapors falls downwardly
into the sums 35 and will be recirculated back
again through each unit through the pipe 36, re-
circulating pump 37 and the riser pipe 38, en-
tering the liquid chamber at the top of the unit.

The vapors thus separated from the liquor in
70 the cylinders 34 will be evacuated upwardly into
the horizontally extending drum 39. It will be
noted that the units consisting of the tube chest,
vapor separator, and recirculation pipes and
pump are identical. Vapor from all of the sep-
arators may be withdrawn from the horizontal

5

drum 38 by the action of a pump, or condenser or other suitable means for evacuating these vapors, through outlet 40.

A difference will be noted between the drum 38 and the series of connected drums 15 shown in Figure 1. These latter drums have flanges which assist in the centrifugal separation of the vapor and droplets. No such flanges are required in the device shown in Figures 7 and 8.

When employing the apparatus shown in Figures 7 and 8 the fresh liquor to be evaporated is introduced through a pipe 41 into the down-flow pipe 36 of the first unit at the right of Figure 7 and is evaporated and recirculated rapidly through the first separator unit according to the same principles applied in the other form of the invention heretofore described. There will be a constant flow of partially concentrated liquor from the sump of the first unit through a pipe 42 into the sump of the second unit and the constant flow of further concentrated liquor from the sump of the second unit through a pipe 43 into the sump of the third unit. From the sump of the last unit the liquor concentrated to a predetermined density will be withdrawn through a pipe 44 by means of the pump 45, which, if desired, may have a variable speed to permit control in the rate of withdrawal.

Heating medium, such as steam, refrigerant gas or other condensable vapor, is preferably introduced into the space surrounding the tubes in chests 30 of Figs. 7 and 8 by means of a common supply pipe 46 and individual inlet pipes such as 47, while the condensate from the heating medium may be withdrawn from the bottom of such space through individual outlets 48 connected to a common outlet duct 49.

While I have shown and described herein, for illustrative purposes, a preferred and alternative embodiment of the invention, it should be understood that considerable variation in the details of construction may be employed without departing from the spirit and scope of the invention, as defined in the following claims.

I claim as my invention:

1. An evaporator comprising a series of vertical tube chests each having vertical tubes and top and bottom plates retaining the tubes, means for supplying heating fluid from a common supply source simultaneously to the space surrounding the tubes in each chest, heating fluid exhaust means connected with each tube chest, top and bottom chambers in each tube chest with which the tubes communicate, removable open ended film feed control tubes resting on the top plates extending downwardly a short distance only into the upper ends of the tubes and rising above the top tube plates, an enlarged vapor separator associated with each chest for extending the vapors received from the lower ends of the tubes and for separating liquid droplets therefrom, the top chamber having an outlet for vapor only through said control and chest tubes, means connected for delivering vapor and droplets from each bottom chamber tangentially into the associated separator for centrifugal flow about a vertical axis in the separator, means connected with the lower portion of each separator including a pump for returning liquid therefrom to the top chamber of the associated tube chest for return flow through said vertical tubes, vapor outlet means connected with the upper portion of each separator, pipes connecting the bottom portions of each separator with the next adjacent separators to effect liquid flow in one direction from

6

the first successively through to the last in the series of separators, means for supplying to the first tube chest-evaporator unit liquid to be evaporated and means for withdrawing from the last in the series of tube chest-evaporator units the concentrated liquid.

2. An evaporator comprising a series of vertical tube chests each having vertical tubes and top and bottom plates retaining the tubes, means for supplying heating fluid to the space surrounding the tubes in each chest, heating fluid exhaust means connected with each tube chest, top and bottom chambers in each tube chest with which the tubes communicate, removable open ended film feed control tubes resting on the top plates extending downwardly a short distance only into the upper ends of the tubes and rising above the top tube plates, an enlarged vapor separator associated with each chest for expanding the vapors received from the lower ends of the tubes and for separating liquid droplets therefrom, the top chamber having an outlet for vapor only through said control and chest tubes, means connected for delivering vapor and droplets from each bottom chamber tangentially into the associated separator for centrifugal flow about a vertical axis in the separator, means connected with the lower portion of each separator including a pump for returning liquid therefrom to the top chamber of the associated tube chest for return flow through said vertical tubes, vapor outlet means connected with the upper portion of each separator, pipes connecting the bottom portions of each separator with the next adjacent separators to effect liquid flow in one direction from the first successively through to the last in the series of separators, means for supplying to the first tube chest-evaporator unit liquid to be evaporated and means for withdrawing from the last in the series of tube chest-evaporator units the concentrated liquid.

3. An evaporator comprising a series of vertical tube chests each having vertical tubes and top and bottom plates retaining the tubes, means for supplying heating fluid to the space surrounding the tubes in each chest, heating fluid exhaust means connected with each tube chest, top and bottom chambers in each tube chest with which the tubes communicate, removable open ended film feed control tubes resting on the top plates extending downwardly a short distance only into the upper ends of the tubes and rising above the top tube plates, an enlarged vapor separator associated with each chest for expanding the vapors received from the lower ends of the tubes and for separating liquid droplets therefrom, the top chamber having an outlet for vapor only through said control and chest tubes, means connected for delivering vapor and droplets from each bottom chamber into the associated separator, means connected with the lower portion of each separator including a pump for returning liquid therefrom to the top chamber of the associated tube chest for return flow through said vertical tubes, vapor outlet means connected with the upper portion of each separator, pipes connecting the bottom portions of each separator with the next adjacent separators to effect liquid flow in one direction from the first successively through to the last in the series of separators, means for supplying to the first tube chest-evaporator unit liquid to be evaporated and means for withdrawing from the last in the series of tube chest-evaporator units the concentrated liquid.

4. An evaporator comprising a series of ver-

tical tube chests each having vertical tubes and top and bottom plates retaining the tubes, means for supplying heating fluid from a common supply source simultaneously to the space surrounding the tubes in each chest, heating fluid exhaust means connected with each tube chest, top and bottom chambers in each tube chest with which the tubes communicate, removable open ended film feed control tubes resting on the top plates extending downwardly a short distance only into the upper ends of the tubes and rising above the top tube plates, an enlarged vapor separator associated with each chest for expanding the vapors received from the lower ends of the tubes and for separating liquid droplets therefrom, the top chamber having an outlet for vapor only through said control and chest tubes, means connected for delivering vapor and droplets from each bottom chamber tangentially into the associated separator for centrifugal flow about a vertical axis in the separator, means connected with the lower portion of each separator including a pump for returning liquid therefrom to the top chamber of the associated tube chest for return flow through said vertical tubes, a common vapor withdrawal duct mounted upon and in unrestricted communication with the upper ends of all of the vapor separators, pipes connecting the bottom portions of each separator with the next adjacent separators to effect liquid flow in one direction from the first successively through to the last in the series of separators, means for supplying to the first tube chest-evaporator unit liquid to be

evaporated and means for withdrawing from the last in the series of tube chest-evaporator units the concentrated liquid.

JOSEPH A. CROSS.
